ABRADING MACHINE

Charles Warren Drake, Kirkwood, Mo., assignor to
McDonnell Aircraft Corporation, St. Louis, Mo.,
a corporation of Maryland

Application April 3, 1943, Serial No. 481,668

3 Claims. (Cl. 51—143)

This invention relates to abrading machines. The invention has for its principal object to devise an abrading machine that will produce open or closed bevels whose slant or inclination may be changed during the beveling operation, that will indicate the angle of the open or closed bevel for which the device is set, that will permit the angle of the bevel to be varied or even reversed during the beveling operation without adjusting the work relative to the supporting table therefor and without stopping the abrasive machine, and that will provide a seat for the operator and permit the angle of the bevel to be controlled by the operator's feet. The invention consists in the abrading machine and in the construction, combinations and arrangements of parts hereinafter described and claimed.

In the accompanying drawings which form part of this specification and wherein like symbols refer to like parts wherever they occur,

Fig. 1 is a fragmentary side elevational view of an abrading machine embodying my invention.

Fig. 2 is a front elevational view of said machine, with the lower portion thereof shown broken away and with the operator's seat omitted.

Fig. 3 is an enlarged fragmentary horizontal section on the line 3—3 in Fig. 1.

Fig. 4 is an enlarged fragmentary side elevational view of the machine in the region of the right-hand rear corner portion of the work supporting table; and

Fig. 5 is a fragmentary vertical section on the line 5—5 in Fig. 1.

My abrading machine comprises an abrading tool or element in the form of an abrasive belt 1 mounted for vertical rectilinear movement in a suitable supporting framework 2. The work that is to be beveled is supported on a table 3 that is tiltable about the axis of a horizontal supporting shaft 4 located in front of and disposed parallel to the abrasive belt. The rear edge 5 of the table is located close to and parallel with the front or working face of the abrading belt and is beveled on its underside to keep said edge clear of said belt during the tipping motion of said table. The table 3 has lugs 6, 6a depending from the underside thereof that are apertured to receive the supporting shaft 4 therefor. The shaft 4 is supported at one end in a bearing 7 fixed to bracket or arm 8 that projects forwardly from the corresponding side of the framework 2; and said shaft is supported near its opposite end in a bearing 7a mounted on the front end of a supporting rod 8a that projects forwardly from the corresponding side of said framework.

The table tilting mechanism comprises a horizontal shaft 9 journaled in a pedestal bearing 10 fixed to the floor below the front edge of the table. The shaft 9 is provided at its opposite ends with crank arms 11 having pedals 12 fixed to the free ends thereof. The operator occupies a seat 13 located in front of said table and applies his feet to the pedals 12 to rotate said shaft in either direction. As shown in Fig. 1, the seat 13 is of the bicycle type and is mounted for vertical adjustment in a supporting post 14 fixed to the floor. The shaft 9 is provided with a sprocket pinion 15 which has a sprocket chain connection 16 with a sprocket wheel 17 fixed to a horizontal shaft 18 located below the front portion of the table parallel with the table supporting shaft 4. This sprocket driven shaft 18 is journaled at its opposite ends in suitable bearings 19, 19a, the bearing 19 being rigidly secured to the supporting bracket 8 for the table shaft bearing 7 and the bearing 19a being rigid with the table shaft bearing 7a.

One end of the shaft 18 is provided with a bevel pinion 18a that intermeshes with and drives 25 a bevel gear 20 fixed to a horizontal shaft 21 disposed transverse to the shaft 18. The shaft 21 is journaled in suitable bearings 22 provided therefor on a bracket 23 fixed to the right-hand bearing 7a for the table supporting shaft 4. The 30 shaft 21 is provided between its supporting bearings 22 with a worm 24 which meshes with a sector worm gear 25 fixed to a plate 26 that depends from and is rigidly secured to the adjacent right-hand end of the table 3. By this arrangement, the pedal shaft 9 may be rotated in either direction by the operator to tilt the table 3 about the axis of its supporting shaft 4 and thus raise or lower the rear edge 5 thereof relative to the abrasive element B, depending on the direction 35 of rotation of said pedal shaft.

The framework 2 of the machine is provided above the level of the table 3 with mechanism for indicating the particular angle at which said table is set. This indicating mechanism comprises an upright slide bar 27 mounted for vertical sliding movement in a dove-tail slideway 28 provided therefor in the front face of the front flange of an upright angle member 29 whose rear flange is suitably secured to the right-hand 45 side of the framework 2. The vertically movable slide member 27 terminates at its lower end in a forwardly projecting flange or shoe 30 that seats on the ball-shaped free end 31a of the horizontal portion of an L-shaped rod 31 whose 50 vertical portion is adjustably secured by nuts 32

to an arm 33 fixed to the depending plate 26 on the right-hand end of the table 3. The slide bar 27 is yieldably held down on the supporting ball 31a therefor preferably by means of a coil tension spring 34 having its upper end secured to the ball engaging shoe 30 of said slide bar and its other end anchored to a bracket 35 fixed to the right-hand framework 2.

The slide bar 27 terminates above the level of the table 3 in a rigid horizontal arm 36 that is disposed in front of the belt 1 clear of the working surface thereof and terminates at its free end in a vertically disposed rack 37. The rack 37 intermeshes with a pinion 38 journaled on a horizontal stud 39 that is fixed to and projects rearwardly from the front flange of an angle bracket 40 whose other flange is rigidly secured to the right-hand side of the framework 2, the front flange of said bracket being located in front of the rack arm 36 of the slide bar 27 and said arm working in a vertically elongated slot 41 provided therefor in said other flange of said bracket.

Mounted on the forwardly projecting hub portion of the pinion 38, between the rack arm 36 and the front stud supporting flange of the angle bracket 40 is a circular dial 42 which is secured to said pinion for rotation therewith preferably by means of a nut 43. The dial has a forwardly and outwardly inclined rim flange 44 whose inner peripheral surface is circumferentially graduated, as at 46, from zero to forty-five degrees on opposite sides of the zero graduation. A pointer 47 is rigidly secured to the front flange of the stud supporting bracket 40 and extends downwardly therefrom with its lower end in position to cooperate with the graduated surface 46 of the rim 44 of the rotary dial 42.

The gear ratio of the table tilting mechanism is such that for each revolution of the pedal shaft 9, the table 3 will be tilted a definite number of degrees and the connection between the table and the rotary dial 42 is such that the pointer will indicate when the table is in a horizontal position and the angular position of the table when the rear edge thereof is raised to produce a closed bevel or lowered to produce an open bevel. In operation, the operator occupies the seat 13 in front of the table 3, the work (not shown) is placed on the table and held against the belt 1 by the operator's hands, and the pedal shaft 9 is operated by the operator's feet until the dial 42 indicates the angle of the surface that is to be beveled. If an open angle is desired, the pedal shaft is rotated in one direction and if a closed angle is desired, the pedal shaft is rotated in the opposite direction. The rotary movement of the pedal shaft 9 is transmitted through the sprocket chain 16 to the shaft 18, thence through the bevel pinion 18a and gear 20 to the intermeshing worm 24 and worm sector gear 25, thereby rotating the table 3 about the axis of its supporting shaft 4. This rotary or tilting movement of the table 3 raises or lowers the rear edge thereof and the L-shaped ball carrying arm rod 31 fixed thereto, thereby imparting a corresponding movement to the vertical slide bar 21 and the rack arm 36 fixed thereto and thus rotating the pinion 38 and the dial 42 carried thereby relative to the pointer 47, which coop-

erates with the graduations 46 on the dial to indicate the angular setting of the table for either open or closed bevels.

The hereinbefore described arrangement provides a seat for the operator and enables the table to be adjusted by the feet for both open or closed angles up to forty-five degrees, while the operator's hands are free for use in holding work down on the table and against the abrasive belt. An important advantage of the present machine is that it makes it possible to produce a bevel which may be varied or even reversed without lifting the work from the table or without stopping the abrasive machine or the beveling operation to change the angle of the bevel. In other words, an open bevel may be started at one end of the work piece and may be changed to a closed bevel at the other end thereof in one continuous beveling operation.

The hereinbefore described invention admits of considerable modification. Therefore, I do not wish to be limited to the precise arrangements shown and described.

What I claim is:

1. A beveling machine comprising a vertically moving abrading belt, a table mounted for tilting movement on a horizontal axis disposed substantially parallel with the working face of said belt, foot controlled means for tilting said table on said axis including a pedal actuated shaft, a shaft driven thereby, and a worm and worm gear connection between said last mentioned shaft and said table, and means for indicating the angular position of said table, said indicating means including a rotary dial responsive to the tilting movement of said table and a stationary pointer cooperating with said dial.

2. A beveling machine comprising a vertically moving abrading belt, a table mounted for tilting movement on a horizontal axis disposed substantially parallel with the working face of said belt, foot controlled means for tilting said table on said axis, and means for indicating the angular position of said table, said indicating mechanism comprising a vertically reciprocable member responsive to the tilting movement of said table, a rack carried by said member, a pinion intermeshing with and actuated by said rack, a dial rotatable with said pinion and a fixed pointer cooperating with said dial.

3. A beveling machine comprising a vertically moving abrading belt, a table mounted for tilting movement on a horizontal axis disposed substantially parallel with the working face of said belt, foot controlled means for tilting said table on said axis, and means for indicating the angular position of said table, said foot controlled table tilting means including a sector worm gear fixed to said table concentric with said horizontal axis, a worm intermeshing with said gear, and a pedal actuated shaft operatively connected to said worm rotating the same, said indicating mechanism including a vertically reciprocable member responsive to the tilting movement of said table, a rack carried by said member, a pinion intermeshing with and actuated by said rack, a dial rotatable with said pinion and a fixed pointer cooperating with said dial.

CHARLES WARREN DRAKE.
